Attorney.

UNITED STATES PATENT OFFICE.

FRANK E. GUTTERSON, OF BROOKLYN, NEW YORK, ASSIGNOR OF ONE-HALF
TO HENRY H. HOWARD, OF EAST ORANGE, NEW JERSEY.

SEAL.

SPECIFICATION forming part of Letters Patent No. 531,376, dated December 25, 1894.

Application filed April 12, 1894. Serial No. 507,213. (No model.)

To all whom it may concern:

Be it known that I, FRANK E. GUTTERSON, a citizen of the United States, residing at Brooklyn, in the county of Kings and State of New York, have invented certain new and useful Improvements in Seals, of which the following is a specification, reference being had therein to the accompanying drawings.

My invention relates to that class of seals composed of lead or other soft compressible material and used for sealing railway cars, baggage, &c., the object of my invention being to provide a seal, of the class referred to, which may be cheaply produced and in which the wire shackle is so firmly anchored in the seal that the latter cannot be tampered with without being badly mutilated or destroyed, thus effectively providing against fraud.

In the accompanying drawings Figure 1 is a plan view of my improved seal before the same has been compressed by the dies of a sealing press. Fig. 2 is a side elevation and Fig. 3 is a section of the same, a portion of the wire shackle being omitted. Fig. 4 is a perspective view showing the wire shackle in the form it will assume when the seal has been compressed. Figs. 5 and 6 are top and side views, respectively, of the seal after it has been compressed. Figs. 7 and 8 show two forms of my invention differing slightly from that illustrated in Figs. 1, 2 and 3.

The body of my improved seal consists of the base A, the neck b and the cap or disk c. The neck b is provided with a transverse hole d and the base A may be provided with a conical or concave recess e to render the crushing of the neck or post comparatively easy, so that too great pressure will not be required in the sealing operation. One end of the wire shackle f is provided with a hook or loop g extending up into the neck b in such position as to partly encircle the hole d in said neck, the metallic seal being cast onto this end of the wire shackle, so that the wire will be embedded in the seal, the free end of the wire shackle being passed through the said hole d and then wound around the neck b, as shown in Fig. 1. With the ends of the shackle thus disposed, relative to the seal, when the latter is compressed the hook or loop g of the shac-

kle-wire will be bent over onto and around the other or free end of the wire passing through the hole d and be compressed down upon the said free end as shown in Fig. 4; and it will be readily understood that with the two ends of the wire shackle thus engaged with each other it will be practically impossible to tamper with the seal without destroying the same, for the reason that the two ends of the wire shackle are firmly locked together. 55 This result is largely due to the fact that the hole d in the neck c is so placed as to be transverse to the length of the shackle wire f, so that to pass the free end of the said shackle wire through the said hole, and wind it about 60 said neck, it will be necessary to bend said wire at a right angle, or approximately so, and thus when the seal is compressed the two ends of the shackle wire will be securely locked together. 65

Various modifications may be made in the details of the seal without departing from the essential features of my invention. For example, the edges of the base A, and the cap or disk c may be beveled, as shown in Fig. 7, 70 or may be rounded as shown in Fig. 8, and the recess in the said base may also be omitted, if desired, as shown in these two figures. Also the loop or hook g at the fixed end of the shackle wire f embedded in the seal may be 75 closed as shown in Fig. 8 instead of being open as shown in Figs. 3 and 7, the open loop or hook, however, shown in said Figs. 3 and 7, being practically closed when the seal is compressed. 80

It will be understood that a sealing press with any suitable form of dies may be used in compressing my improved seal, these dies or the sealing press, however, not forming any part of my present invention. 85

Having thus described my invention, I claim and desire to secure by Letters Patent— 90

The combination with a metallic seal consisting of the base A, the neck b, provided with the hole d, and the cap or disk c, of the shackle wire f one end of which is provided with a hook or loop g embedded in said seal and extending into said neck around said hole, and the other or free end of which is to be 95 100

passed through said hole and wound about said neck, the said hole ^{is} being transverse to the length of the said shackle wire, so that the free end of the latter will be bent at a right angle, or approximately so, to its length, to pass it through said hole and wind it about said neck.

In testimony whereof I affix my signature in presence of two witnesses.

FRANK E. GUTTERSON.
